BOTTLE HANDLING MECHANISM

Robert J. Wynne, Bellwood, Ill., assignor to
Irving D. Porter, River Forest, Ill.

Application September 27, 1933, Serial No. 691,124

4 Claims. (Cl. 198—20)

My invention relates to improvements in bottle handling mechanism, and has for a particular object the provision of mechanism for effecting the discharge of bottles from a bottle washing machine of the type having a soaking tank, conveyor for conveying bottles through said soaking tank, spraying cleansing means, and means for discharging the bottles from the conveyor after receiving cleansing treatments in the soaking tank and from the spraying cleansing means.

Different kinds of mechanism have been used, including power actuated rams, for pushing the bottles from their conveying cups, but these have proved unsatisfactory in some particulars such as danger from contamination, difficulty of adjustment, and danger of damaging bottles. Others have used what might be termed gravity discharge mechanism, but these have proved ineffective at times because of their failure in ejecting bottles. Others have failed because the bottles have been subjected to a drop of considerable distance, causing breakage and toppling of the bottles. Since these machines are adapted to operate at comparatively high speed, and are usually cared for by one attendant, any one of the above difficulties causes unsatisfactory operation.

An object of my invention is the provision of discharge mechanism which will eliminate the above mentioned difficulties and discharge the bottles accurately, safely, and without any danger of contamination from discharging rams.

The discharging mechanism described herein is part of a machine which is shown and described in my copending applications filed on even date herewith, and entitled respectively "Bottle washing and conveying mechanism," given Serial No. 691,122, and "Bottle handling mechanism," given Serial No. 691,123.

A better understanding of my invention may be had by reference to the accompanying drawings, in which:

Fig. 1 is a side elevational view of the portion of the type bottle washing machine described, and incorporating my bottle handling mechanism;

Fig. 2 is an end view, partly in section and partly in elevation, taken substantially on the line 2—2 of Fig. 1;

Fig. 3 is a sectional view, taken substantially on the line 3—3 of Fig. 2;

Fig. 4 is a view, partly in section and partly in elevation, showing my bottle handling mechanism in the opposite stage of operation from that shown in Fig. 3;

Fig. 5 is a top plan view of the bottle conveying cups preferably employed in my machine;

Fig. 6 is a sectional view, taken substantially on the line 6—6 of Fig. 5;

Fig. 7 is a detail view of the ejecting arm and table lowering arm employed in my bottle handling mechanism;

Fig. 8 is a sectional view, taken substantially on the line 8—8 of Fig. 2, and illustrates the operating mechanism for the removing conveyor;

Fig. 9 is a detail view, taken substantially on the line 9—9 of Fig. 8;

Fig. 10 is a detail view, partly in section and partly in elevation, and taken substantially on the line 10—10 of Fig. 3; and

Fig. 11 is a detail view, taken substantially on the line 11—11 of Fig. 10.

Referring now to the drawings, the main washing machine comprises a main housing 20 having side walls 21 and 22, and framework generally indicated at 23. Endless conveyor chains 24 travel on trackways 25 which are mounted on side walls 21 and 22. Sprockets 26 receive the chains 24, and shafts 27 extend transversely of the machine and support sprockets 26. Appropriate bearings are mounted in side walls 21 and 22 for the reception of the ends of shafts 27. Other sprockets are located at the opposite end of the machine from that shown in Fig. 1, but are not shown in this application. A soaking tank 28 is provided at the lower portion of the machine between side walls 21 and 22, and conveyor chains carry bottle cups 29 through the soaking tank during the operation. Cleansing spraying means 30 act on the bottles on the return movement of the conveyor chains.

A motor (not shown) transmits power to a gear reduction box 31 supported on transversely extending frame members of frame 23, and shaft 32 extends from gear reduction box 31 and carries sprockets 33 which mesh with chains 34. A main power takeoff shaft 35 has sprockets 36 keyed thereto, and chains 34 drives sprocket 35. A pair of crank arms 37 are keyed to transversely extending shaft 35, and pins 38 connect longitudinally extending connecting rods 39 to crank arms 37. Pins 40 connect the opposite ends of connecting rods 39 to legs 41 of bell cranks 42. Spaced bell cranks 42 are keyed to a transversely extending shaft 43 having its bearings in side walls 21 and 22, and a pair of arms 44 are keyed to shaft 43. A pair of adjustable conveyor advancing members 45 and 46 are pivotally received by arms 44.

Conveyor advancing members 45 and 46 are

110

provided at their upper ends with chain engaging ends 47 which are adapted to partially embrace rollers 48 of conveyor chains 24. Cam surfaces 49 are provided at the ends of conveyor advancing members 45 and 46 for engagement by elevating deflecting plates 50 which are provided with longitudinally extending flanges 51, and are secured to the side walls 21 and 22 of housing 20 by angle brackets 52.

10 The opposite legs 53 of bell cranks 42 extend forwardly and pivotally receive stub shafts 54 and 55. A feeding conveyor connecting rod 56 is pivotally received by stub shaft 54 and extends forwardly to link 57, and is pivotally connected by pin 58. Link 57 is pivotally received by a transversely extending feeding conveyor shaft 59 which supports feeding conveyor sprockets 60 for cooperation with feeding conveyor chain 61 and feeding conveyor belt 62. A feeding pawl 63 is pivotally received by pin 58 for cooperation with pawl engaging members 64 on the conveyor belt 62. The feeding conveyor may be supported at the forward end of the machine by longitudinally extending attaching plates 65 which are secured 25 to side walls 21 and 22 of housing 22, and by a depending leg 66.

Feeding conveyor connecting rod 56 is formed of a section 67 which is telescopically received by a section 68. A pair of oppositely disposed longitudinal slots 69 in section 68 cooperate with transversely extending pin 70 of section 67, and thus provide lost motion between leg 53, bell crank 42, and link 57.

30 The downward actuation of bell crank 53 causes the downward movement of connecting rod 56, and thus draws link 57 toward the bottle receiving mechanism of the machine, and causes pawl 63 to engage pawl engaging members 64 in order to move conveyor belt 62. As the belt 62 is advanced, a series of bottles toward the end of conveyor belt 62, as shown in Fig. 4, topple forwardly and impinge upon depending swinging cushions 71 which are hingedly connected to a transversely extending bracket 72 which may be secured to the transversely extending forward plates of removing conveyor unit 73. The cushions 71 swing toward the receiving mechanism of the machine and permit the bottles to topple downwardly with their necks foremost into inclined bottle chutes 74 which are arranged longitudinally of the machine and supported by a transversely extending angle bracket 75. The bottles then slide downwardly through depending swinging chutes 76 and enter bottle cups 29.

35 Bottle cups 29 are shown in detail in Figs. 5 and 6, and are formed of counterpart sections 77 which extend transversely of the machine and have attaching lugs 78 secured by bolts 79 to L-shaped lugs 80 which are secured to the inside links 81 of conveyor chains 24. The side walls of cups 29 are provided with a plurality of depending fingers 82 which extend inwardly toward each other from the outside walls of cups 29, and provide vertical longitudinal slots 83 for the reception of cushioning pins 84. The pins 84 depend through slots 83, as shown particularly in Fig. 4, and cushion the fall of bottles into cups 29. As legs 53 of bell crank 42 are raised from the position shown in Fig. 4 to the position shown in Fig. 1 the pins 84 are drawn upwardly from slots 83 and permit the bottles to descend to the full depth of bottles 29. At the time the legs 53 move upwardly legs 41 move downwardly, and arms 44 carrying adjustable conveyor advancing members 45 and 46 are also forced downwardly

so as to cause chain engaging ends 47 to engage the rollers 48 of chains 24 and advance the conveyor chains one step.

Successive actuations of bell crank 42 cause the movement of the series of bottles through soaking tank 28 where they receive soaking treatment. During their movement by conveyor chains 24 the bottles are brought from the downwardly inclined position shown in Fig. 4 through a horizontal position to an upright position, and during this latter period ride on bottle guides 85 which prevent the bottles from slipping outwardly from the bottle cups. At the opposite end of the machine the bottles are inverted and brought back by the conveyor chains 24 to receive cleansing spraying treatments from cleansing spraying means 30 while still in an inverted position. After receiving these treatments the bottles are brought back toward the receiving end of the machine, while sprockets 26 cause chains 24 to bring the bottles to a partially upright position, at which time the bottles slide partially from cups 29 and drop to bottle guide plate 86.

Bottle guide plate 86 is secured at its upper end and is free at its lower end, and may be adjusted vertically by adjusting screw 87 which passes through and is anchored to the transverse wall of housing 20. The free end of plate 86 ends adjacent the upper surface of a transverse roller 88 which is mounted on a transversely extending shaft 89 having spindles 90 which are received by appropriate bearings in roller supporting brackets 91. Brackets 91 are supported by the longitudinally vertically extending flanges of angle irons 92 and 93. A sprocket 94 is keyed to shaft 89 at a point between the end of roller 88 and supporting bracket 91.

A horizontal transverse bottle lowering table 95 is secured by screws 96 to table supporting base 97. Vertical slots 98 in base 97 receive table supporting posts 99, and posts 99 are secured to base 97 by pins 100 which extend through base 97 and posts 99. Posts 99 are slidably received in vertical slots 101 in transverse supporting tie bar 102. Stop lugs 103 secured to supporting brackets 104, are secured to transversely vertically extending flanges of angle irons 92 and 93 by bolts 105, and serve to limit the upward vertical movement of table supporting base 97. Although the posts 99 are slidably received in slots 101 of tie bar 102, they are frictionally maintained in various positions relative to said tie bar.

A longitudinal threaded bore 106 at each end of tie bar 102 receives a screw plug 107 which presses against a compression spring 108, which in turn presses upon the enlarged head 109 of friction stop member 110. A restricted opening 111 communicates with vertical slots 101, and a restricted friction head 112 protrudes through opening 111. Friction head 112 contacts with flattened portion 113 on table supporting post 99.

The ends of tie bar 102 are provided with spindles 114 which protrude through opposed spaced sliding blocks 115 and 116 which are received in grooves 117 and 118, respectively. Grooves 117 and 118 are formed between the transversely extending flanges of a pair of spaced angle irons 98 and 119 and angle irons 92 and 120, respectively.

As before stated, spindles 114 pass through sliding blocks 115 and 116 which are slidably in grooves 117 and 118, and the spindles 114 extend entirely through grooves 117 and 118 and laterally of the machine a considerable extent. Spacing sleeves 121 are received on spindles 114 and 150

serve to space table lowering arms 122 and 123 which are pivotally mounted on spindles 114 and held in place by collars 124. The opposite ends of table lowering arms 122 and 123 are pivotally received by stub shafts 54 and 55. As before stated, stub shafts 54 and 55 are received by the outer ends of bell crank legs 53.

Adjacent the lower ends of arms 122 and 123 are secured adjustable cam shoes 125 and 126 which are on the insides of the table lowering arms and are adapted to contact with and operate on cams 127. The cams 127 are formed on the lower end of a pair of spaced bottle ejecting arms 128 which are pivotally mounted on the lower sprocket shaft. From shaft 27 arms 128 extend upwardly and pivotally receive a transverse shaft 129 which is provided with a pair of longitudinal slots 130 for the reception of the legs 131 of U-shaped bottle ejecting member 132. Arcuate slots 133 in side walls 21 and 22 permit of oscillatory movement of shaft 129 when cam shoes 125 and 126 are forced downwardly and push bottle ejecting arms 128 forwardly. Stop lugs 134 are keyed to shaft 129 at a point adjacent the arms 128 and abut against stops 135 so as to limit the downward movement of bottle ejecting member 132. Spring supporting brackets 136 mounted on arms 128 receive the ends of returning coil springs 137 which extend away from the receiving end of the machine and are secured to eye bolts 138 to vertical channel iron flanges 139 of framework 23.

As has been before stated, sprocket 94 is keyed to shaft 39, and lies in a plane which is longitudinal of the machine. A chain 140 meshes with the teeth of sprocket 94, and one end of the chain is secured to chain supporting bracket 141 mounted on the top horizontal surface of tie bar 102. After being engaged by sprocket 94 the chain extends upwardly and away from the receiving end of the washing machine and is received by a grooved pulley 142 which is pivotally mounted on side wall of housing 20. From the groove of pulley 142 the chain passes downwardly to and is secured to one end of a coil spring 143, the other end of which is anchored by a pin 144 to conveyor advancing member. From this arrangement it can be seen that the downward movement of conveyor advancing member 46 will cause the clockwise rotation of roller 88 as viewed in Figs. 3 and 11, and likewise a downward movement of tie bar 102 and upward movement of conveyor advancing member 46 will cause rotation of roller 88 in a counter-clockwise direction.

Spanning the space between angle irons 92 and 93, and lying in a horizontal plane, is an angle stop member 145, against which the front edge of table 95 abuts when table lowering arms 122 and 123 are brought downwardly to the position shown in Fig. 4. The front edge of the table strikes stop 145 before the arms 122 and 123 have reached the full limit of their travel, and consequently tie bar 122 is slid downwardly on table supporting posts 99 and assumes the position shown in Fig. 4.

The removing conveyor 73 is provided with a pair of transversely extending angle iron trackways 146 whose upper horizontal faces are lying in substantially the same plane as the horizontal face of angle iron stop 145. Rear conveyor supporting plates 147 and 148 are secured adjacent the ends of trackways 146 and extend vertically thereof. Adjacent the inner vertical edges of plates 147 and 148 are secured vertical angle irons 149 with their transverse flanges lying parallel to the transverse faces of plates 147 and 148,

and with their longitudinal flanges anchored on the longitudinal flanges of angle irons 92 and 93. Front vertical plates 150 and 151 are secured to the vertical flange of front trackway 146, and channel irons 152 hold the front plates and rear plates in fixed spaced relation.

Rear plates 147 and 148 support conveyor shaft bearings 153, and front plates 150 and 151 support conveyor shaft bearings 154. Conveyor shafts 155 and 156 are mounted in bearings 153 and 154, and conveyor sprockets 157 are keyed to shafts 155 and 156 at a point between bearings 153 and 154. Front plate 151 is apertured to permit the shaft 156 to extend therethrough. A ratchet disc 158 is keyed to the extending portion of shaft 156, and is provided with pawl engaging notches 159. A pawl carrying disc 160 is loosely mounted on shaft 156, and has gravity operated pawls 161 pivotally mounted thereon. A sprocket 162 is secured to pawl carrying disc 160 by a plurality of spaced bolts 163, and collar 164 maintains sprocket 162 and pawl carrying disc 160 in proper position on shaft 156, but permits sufficient clearance between the meeting faces of ratchet disc 158 and pawl carrying disc 160 so that the pawl carrying disc 160 may rotate on shaft 156 independently of ratchet disc 158.

An endless chain 165 meshes with the sprockets 157, and has L-shaped lugs 166 secured to the side links of said chain. A plurality of conveyor belt links 167 are secured to lugs 166 by bolts 168. The conveyor belt links 167 rest upon conveyor trackways 146 during the movement of chain 165 around sprockets 157.

Chain 169 meshes with the teeth of sprocket 162 and has a depending end 170 secured to the eye 171 of counterweight 172 which is mounted in a cylindrical housing 173. Housing 173 extends vertically of the machine and is secured to the side wall 21. The other end 174 of chain 169 extends downwardly and is secured to an eye 175 in an arm 176 by a link 177. Arm 176 is secured to table lowering arm 122 adjacent the lower end thereof, and at an angle of substantially 90 degrees. An L-shaped guard 178 is secured to the front plate 151 and extends outwardly and downwardly therefrom so as to cover the end of shaft 156 and sprocket 162.

It has been heretofore explained how the bottles are fed into the machine, conveyed therethrough, and brought to adjustable guide plate 86. As a series of bottles reaches the position indicated at 179 the parts of the machine are in the relation shown in Fig. 3, and the preceding series of bottles has been deposited upon table member 95. The next movement of the machine from the position shown in Fig. 3 causes the table 95 to be lowered, and of course conveyor advancing members 45 and 46 are brought to their highest position and cam surfaces 49 ride on elevating deflecting plates 50. During this upward movement the end of the chain anchored to bracket 141 is drawn downwardly and roller 88 is rotated in a counter-clockwise direction, but since there is no series of bottles immediately above roller 88, this counter-clockwise rotation has no effect. However, as conveyor advancing members 45 and 46 start downwardly and their ends 47 engage rollers 43, the series of bottles indicated at 179 is brought forwardly and the lowermost portions of the bottles are slid from plate 86 to the topmost surface of roller 88. Roller 88 is being rotated in a clockwise direction by the movement of chain 140 on sprocket 94, and due to the movement of members 45 and 46 and

the number of teeth in sprocket 94, the rotation of roller 88 is quite rapid.

The coiled spring 143 takes up any slack in chain 140 during any stage of movement. The 5 rotation of roller 88 causes the bottles resting thereon to be shifted from one side of the bottle cups to the other, and aids in loosening them from the cups, and when the conveyor advancing members have advanced the conveyor chains a sufficient distance the bottles are dropped a short 10 distance to table 95 which has been brought to the position indicated in Fig. 3 during the time the conveyor advancing members have been moving the conveyor chains. It can be seen that the 15 vibration and agitation of the bottles which is caused by the rotation of roller 88 aids them in dropping to the table. Since the roller is rotating quite rapidly, it will cause the bottle to be brought more quickly to the vertical position 20 shown at 180 in Fig. 3.

As the conveyor advancing members 45 and 46 were being raised, the table lowering arms 122 and 123 were being drawn downwardly by bell crank legs 53 so as to clear table 95 of the series 25 of bottles thereon, and as the conveyor advancing members 45 and 46 were lowered, the table lowering arms 122 and 123 were forced upwardly from the position shown in Fig. 4. From Fig. 4 it can be seen that the downward movement 30 of arms 122 and 123 caused table 95 to be lowered until it reached stop 145, and further movement of the arms caused the tie bar 102 to slide downwardly on table supporting posts 99. When arms 122 and 123 start upwardly to receive a 35 series of bottles from roller 88 the friction stop members 110 will bear against table posts 99 and maintain the spaced relation between table 95 and tie bar 102 until stop lugs 103 prevent the further upward movement of table supporting base 97, and then tie bar 102 will again slide on 40 posts 99 until it reaches substantially the position shown in Fig. 10 relative to table supporting base 97. This construction causes the table 95 to be brought to bottle receiving position a period of time in advance of the final part of 45 the movement of conveyor chains 24 by the conveyor advancing members, and thus the table is always in bottle receiving position before a series of bottles is advanced a sufficient distance to be- 50 come free from the support of roller 88.

After the bottles have passed over roller 88 and come to a rest on the table 95, table lowering arms 122 and 123 are drawn downwardly, bringing the bottles downwardly out of the cups, and 55 table 95 is brought to stop 145, where the bottles are in position to be shoved forwardly onto the conveyor belt of the removing conveyor. As before explained, the arms 122 and 123 then continue downwardly, leaving table 95 resting on 60 stop 145. The continued downward movement causes cam shoes 125 and 126 to be brought in contact with and operate on cams 127. The movement of shoes 125 and 126 on the cams 127 causes arms 128, transverse shaft 129, and U-shaped bottle ejecting member 132 to move forwardly from the position shown in Fig. 3 to that 65 shown in Fig. 4. The cross member of the bottle ejecting member 132 pushes the bottles from table 95 onto conveyor belt links 167. When table lowering arms 122 and 123 again start upwardly the returning springs 137 aid cam shoes 125 and 126 in returning arms 128 to the position 70 shown in Figs. 1 and 3. However, the failure of the cams and returning springs would not cause damage to U-shaped bottle ejecting member 132,

since it is mounted in the pivoted transverse shaft 129, and the forward end of the member 132 will be raised by the table 95 until the table passes upwardly a sufficient distance to clear the member 132. The member 132 will then swing downwardly by gravity until stop lugs 134 come in contact with stop pins 135.

The bottles on conveyor belt links 167 will remain in the position shown in Fig. 2 during the period of time when the table lowering arms 80 122 and 123 are being raised to receive another series of bottles. When the arms 122 and 123 start downwardly the arm 122 carries with it arm 176, and the end 174 of chain 169. Downward movement of the end 174 of chain 169 85 causes the rotation of sprocket 162 and the pawl carrying disc 160. The rotation of pawl carrying disc 160 is in a counter-clockwise direction, as shown in Fig. 9, and the gravity operated pawls 161 drop into notches 159 of ratchet 90 disc 158. Further rotation of the sprocket 162 causes the shaft 158 to be rotated in a counter-clockwise direction and rotate sprocket 157. Sprocket 157 causes the movement of removing conveyor chain 165, and the series of bottles 100 shown in Fig. 2 are removed to the left thereof to a suitable supplemental conveyor (not shown) before another series of bottles is pushed from table 95. The counterweight 172 carries the end 170 of chain 16 downwardly when the arm 105 176 is raised.

A light 181 is placed in the concaved portion of a curved light reflecting plate 182, and the bottles may be inspected by the operator when the bottles are on the removing conveyor belt 110 before the belt is moved. The bottles remain on the removing conveyor belt for the period of time while the table lowering arms are moving upwardly, and until they start moving downwardly.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of the appended claims.

Having thus described my invention, what I claim as new and desire to secure by Letters Patent is:

1. Bottle handling mechanism comprising conveying means and bottle carrying cups mounted on said conveying means, means for guiding said conveying means through a semi-circular path, means for retaining bottles in said cups during the movement of the conveying means and bottle carrying cups through the semi-circular path, roller means adjacent the end of said retaining means for receiving bottles from said retaining means being adapted through rotation to bring said bottles into a vertical position, means for rotating said roller means, and a vertically movable table adjacent said roller means and adapted in one position thereof to receive bottles from said roller in an upright position, and means for moving said table in a vertical path.

2. In a bottle washing machine having a continuous conveyor with bottle carrying cups mounted thereon, discharge mechanism including a guide plate, a roller mounted adjacent the end of said guide plate, a table movable into and out of a position adjacent said roller, means

for moving said table, and means for removing bottles from said table; said last mentioned means being under the control of the means for moving said table.

5 3. Bottle washing mechanism comprising conveying means and bottle carrying cups mounted on said conveying means, means for guiding said conveying means through a substantially semi-circular path, means for retaining bottles in said cup during the movement of the conveying means and bottle carrying cups through their semi-circular path, roller means adjacent the end of said retaining means for receiving bottles in an inclined position from said retaining means, means for rotating said roller means so as to bring said bottles from an inclined position in which they are received from said retaining means to a vertical position, a vertically movable table adapted to be moved into position adjacent said roller means so as to receive bottles from said roller means, said roller means also being adapted through rotation at a relatively high rate of speed to cause vibration and consequent loosening of bottles in their cups, and means for moving said table in a vertical path to receive bottles directly from said cups.
